ABSTRACT: A method of making sheet metal parts by punching blanks and folding them over. The edges of the blanks are indented in the region of the fold line to compensate for material flow when the parts are folded. The parts are made by trimming, using punches with enlarged heads which form the indentations. The sheet is indexed so that the rear of the punch overlaps the cut made by the enlarged head on the previous stroke, to prevent draw-down burr.

This invention relates to the manufacture of sheet metal parts which are punched as blanks from a strip of metal and folded over.

FIG. 1

FIG. 2

INVENTOR
PAUL LOEWENSTEIN

INVENTOR
PAUL LOEWENSTEIN

1
METHOD OF MAKING SHEET METAL PARTS**BACKGROUND OF THE INVENTION**

When a sheet metal blank is formed by bending especially if the blank is folded a full 180°, flow of material due to bending increases the edge to edge dimension in the region of the fold. In parts made to close tolerance requirements, the increase may exceed the tolerance in edge to edge dimension for the part as a whole. Another problem in the production of sheet metal parts is burr formation, due to wear on the punches, or presentation of a previously cut edge at too small an angle with respect to the punch.

The principal object of this invention is to provide a method of making sheet metal parts which makes it possible to produce folded over parts to close tolerances and which eliminates burr formation. Another object is to provide a method which eliminates the need for frequent sharpening of the punches. Other objects, advantages, and novel features will be apparent from the following description.

SUMMARY

The method here disclosed can be used for making parts of any size, but is especially suitable for making parts which are so small that individual inspection and deburring are not economically feasible. The blanks are made by trimming a strip of sheet metal with punches having forward head portions somewhat wider than their body portions. The strip is indexed so that the rear ends of the punches overlap the cuts made by the head portions on the previous stroke. The portions of the strip left after punching are sheared into individual blanks in such a way that the indentations in their edges, formed by the head portions of the punches, be in the region in which the blank is to be folded over to form the finished part.

BRIEF DESCRIPTION OF THE DRAWINGS

In the drawings illustrating the invention:

FIG. 1 is a plan view of the blank of a typical sheet metal part made according to the new method, here disclosed;

FIG. 2 is a side elevation of the part of FIG. 1 in finished condition;

FIG. 3 is a plan view of a typical punch used in making the parts;

FIG. 4 is a fragmentary plan view illustrating the first step in making parts by means of multiple punches from a strip of sheet metal;

FIGS. 5 and 6 are views similar to FIG. 4 illustrating successive steps in forming the parts;

FIGS. 7 and 8 are fragmentary plan views illustrating the effects of wear or rounding of the corners of conventional rectangular punch;

FIG. 9 is a fragmentary plan view illustrating an alternative shape of punch to be used in the new method; and

FIGS. 10 and 11 are fragmentary plan views illustrating the effect of clearance between the punch and the die, when punching material with an already cut edge presented at different angles.

DESCRIPTION OF THE PREFERRED EMBODIMENT

The part, generally indicated by the numeral 20, shown in FIG. 2 is a tab which is subsequently to be clamped over the end or edge of a metal strip. The blank of FIG. 1 has rectangular end portions 20a and 20b and a central portion 20c which is reduced in width by notches 21 formed in the edges of the blank. The part is formed by bending the blank 180° along the dot and dash line 22. In the finished part notches 21 form recessed portions in the region of the bend. The increase in the transverse dimension of central portions 20c, caused by sideward flow of material in the region of the bend, is less than the depth of notches 21. Therefore, in the finished part, the transverse dimension of the central portion 20c does not exceed that of portions 20a and 20b, so that close tolerances in the width of the part as a whole can be maintained.

It is understood that the depth of notches 21 is somewhat exaggerated in the drawings for clarity. On relatively thin stock the notches may be in the neighborhood of a few thousandths of an inch deep. It is necessary only that the depth of the notches be equal to or greater than the expansion of the part in the bend region due to sideward flow of the stock in the bending operation. The amount of flow for a given piece of stock can be readily determined by bending and measuring a sample piece.

10 The blanks for the parts are punched from a strip 25 of sheet metal by means of a multiple die employing a row of punches of the configuration of the punch 26 illustrated in FIG. 1. This punch has a rectangular body portion 26a and a head portion 26b wider than the body portion. The punches are somewhat longer than the blanks to be formed. The punches are so placed in the die that the body portions 26a are spaced from each other by the width of portions 20a, 20b, of the parts. The punches are mounted in a die which may be of any well-known construction. It is understood that the die is provided, in the customary manner, with a female portion having mating cavities of the same configuration as the punches, and that any customary means for advancing and guiding the strip 25 may be used.

25 The first stroke of the punches 26 on the forward edge 25a of the strip produces slots 27 having widened forward end portions 27a corresponding in shape to the head portions 26b of the punches. The strip is then advanced by a distance equal to the length of one of the blanks 20. As shown in FIG. 5, the rear ends of the body portions 26a of the punches now overlap the forward end portions 27a of slots 27.

30 On the next stroke of the die, slots 28 with widened forward end portions 28a are cut out by the punches. The length of slots 28 (including portions 28a) is equal to the length of a blank. The strip is again advanced by the same distance, bringing slots 28 to the position shown in FIG. 6, with the rear ends of the punches overlapping slot portions 28a as they previously did slot portions 27a. The process is repeated as many times as required to use up the strip 25. The strip is sheared, by an operation which may be performed in the same die, along with dot and dash lines 29, producing blanks of the configuration of blank 20.

35 The method here described is a trimming operation, that is the finished parts are made from the portions of stock left after punching, as compared to a true punching operation in which the pieces struck out by the punches form the blanks for the finished parts. The use of punches with enlarged head portions in an overlapping cutting arrangement eliminates burring problems. The more common reason for burr formation can be explained as follows:

40 In FIG. 7, an initially rectangular punch 30 mating with a rectangular die cavity 31 is illustrated as used to punch a piece of stock 32. The stock is indexed between strokes so that the successive cuts are end to end. It is well known that square or sharp corners on punches tend to become rounded by wear. The rounding of the corners on punch 30 is here illustrated as somewhat exaggerated for clarity. The cut 33 made by the punch on the previous stroke has rounded forward corners 33a. When the punch makes the next cut, regions 32a of the stock will form burrs on the finished parts. To prevent the formation of burrs, it is necessary to sharpen the punches frequently.

45 FIG. 8 illustrates the punch of FIG. 7 used to make overlapping cuts. By advancing the stock so that successive cuts overlap in this manner, it would appear that the burr problem is eliminated. That is not the case, however, because of the occurrence of another type of defect sometimes called "draw down" burr, which can be understood by referring to FIGS. 10 and 11.

50 It is necessary to provide a certain amount of clearance between a punch and its mating die cavity. In FIGS. 10 and 11, a punch 33 is shown having a side wall 33a separated from the corresponding sidewall 34a of the die cavity 34 by a gap 35. It is understood that the clearance is greatly exaggerated in the drawings for purposes of illustration. In FIG. 10, a piece of

stock 36 is shown having a cut edge 36a disposed at right angles to the walls 33a and 34a of the punch and die cavity. Under these conditions, the punch will make a clean cut in the stock. In FIG. 11, a piece of stock 37 is shown with a cut edge 37a lying obliquely with respect to walls 33a and 34a when the angle 38 between the cut edge 37a and the walls 33a, 34a becomes too small, the stock between 33a and 34a tends to roll down between the punch and the die before breaking, forming a burr. The angle at which burr formation starts to occur varies with the material. Some materials can be cut satisfactorily when the angle 38 is about 10°. On other materials, about 45° may be the minimum angle which can be tolerated.

When the corners of a rectangular punch have become rounded from wear, and the punch is used for overlapping cuts as illustrated in FIG. 8, the edges of the previous cut in the regions of its forward corners 33a lie almost tangent to the sidewalls of the punch. Under this condition draw down-burr formation will occur as explained in the previous paragraph.

As a practical matter, it is desirable to make the corners, such as corners 26c, of a punch with a radius initially, rather than absolutely square, to reduce corner wear. In the applicant's method, this can be readily done, because the points of contact between the sides of the punch and the forward edge 27c of the previous cut are spaced from the corners 27b of the cut. Even if the latter are rounded, the stock, in the region of contact with the sides of portion 26a of the punch, is still presented at approximately right angles to the punch, so that draw down-burr formation does not occur.

FIG. 9 illustrates a variation in the form of punch which can be used in performing this method. The punch 40 has body

portion 40b and an enlarged forward head portion 40a with bevelled forward surfaces 44 leading to a front surface 45. The cut 41 has a correspondingly-shaped forward portion 41a. It is understood that the material left by the punches is sheared into individual blanks so that portions 41a of the cuts lie in the region of the fold line, as previously described with respect to part 20. At points 42, the cut is at approximately 45° to the sidewalls of the punch. Surface 44 is narrower than body portion 40b so that a constant cut angle of about 45° is maintained at points 42 regardless of wear on the corners of the punch.

The method here described makes it possible to manufacture small parts to close tolerances, free of burrs. The need for sharpening the punches is reduced to a minimum, thus effecting a considerable saving in labor and down time, and also prolonging the life of the punches.

Although the method here described is intended primarily for forming parts from sheet metal, it is understood that the method is applicable to other rigid sheet materials having similar characteristics.

I claim:

1. A method of making parts from a sheet of rigid material which comprises successively punching cuts in said sheet, each cut having a wider portion and a narrower portion, with the wider portion of each cut overlapping the narrower portion of the next cut in succession, at least two rows of such cuts being formed side by side in spaced relationship leaving an intermediate strip with regions of reduced width to form blanks, and bending the blanks in their regions of reduced width.

UNITED STATES PATENT OFFICE
CERTIFICATE OF CORRECTION

Patent No. 3,587,283 Dated June 28, 1971

Inventor(s) Richard P. Davis

It is certified that error appears in the above-identified patent and that said Letters Patent are hereby corrected as shown below:

The sheets of drawings and the drawing on the front page format should be canceled and the attached drawing and drawing figure substituted therefor.

Signed and sealed this 13th day of March 1973.
